CONTACT SELECTOR

William H. Starck, West Chicago, Ill.

Application October 14, 1940, Serial No. 361,181

3 Claims. (Cl. 200—6)

This invention relates in general to improvements in electrical switching means and especially is concerned with a novel electric switch adapted for operation by an oscillating cam.

It is an object of this invention to provide a sensitive electric current control means for use in conjunction with railroad signals of the so-called wigwag type.

Another object of this invention is to provide an electrical switch adapted for operation by an oscillating cam which will indicate current control changes in direction of motion.

A still further object of this invention is to provide an electrical switching means operating by an oscillating cam indicating both change in direction of motion which is extremely sensitive from a practical standpoint and which includes means for magnifying such changes of motion as occur further to promote delicate sensitivity and nicety of adjustment.

An advantage of the novel switch construction according to this invention over similar electrical switches now in use is that in it lost motion is reduced substantially to a minimum with the result that a switch functions substantially instantaneously to indicate changes in direction of motion of the cam by which the switch is operated.

Noteworthy among the features of the novel switch according to the present invention are its simplicity and ruggedness of construction, the former suiting the device to the requirements of manufacture under conditions of mass production and the latter assuring long useful life.

Other objects, advantages and features of the new and improved switch according to the present invention will be apparent to those skilled in this art during the course of the following description.

Regarded in certain of its broader aspects the novel electrical switching device according to the present invention comprises a horizontal vertically swingable first bar, a vertically extending longitudinally reciprocable second bar pivoted near its bottom end to the first bar at a place intermediate the axis of swinging motion of said first bar and a distal end thereof whereby oscillation of the first bar in a vertical plane causes vertical reciprocation of the second bar, a rigid rider on the bottom of the second bar frictionally engaging with the operating cam in a manner such that changes in the position of the cam causes vertical reciprocation of the second bar and swinging of the first bar and changes in direction of motion of the cam cause oscillation

of the second bar about the pivotal connection to the first bar, and switches operated by swinging of each of said bars.

In order to facilitate a fuller and more complete understanding of the present invention a specific embodiment thereof herein illustrated will be hereinafter described, it being clearly understood, however, that the illustrated embodiment, although presently preferred, is provided solely by way of example of the practice of this invention and not by way of limitation thereof except insofar as the invention is recited in the subjoined claims.

Referring now to the drawing,

Figure 1 is substantially a front elevational view of the presently preferred embodiment of this invention showing the same mounted adjacent an operated cam,

Fig. 2 is essentially a side elevational view of the device in Fig. 1, and

Fig. 3 is a top plan view thereof.

The herein illustrated presently preferred embodiment of this invention generally designated by the reference character 10 comprises, it will be noticed, an electrical insulative base 11 upon which is mounted by means of a pin 12 and spacer sleeve 13 a horizontally positioned vertically swingable first bar 14. It is to be noticed that the pin 12 is received in the first bar 14 near one end thereof and that the first bar is held in position thereon by a cotter pin 12a. A vertically adjustable L-shaped member 15 mounted upon the base 11 by screws 16 is disposed in a manner such that a portion 15a thereof extends beneath and, upon occasion, can support the first bar 14 to limit downward swinging motion thereof.

A substantially vertical second bar 17 pivoted near its bottom end by a pin 18 to the first bar 14 at a place intermediate the pin 12 and the distal free end of the first bar is held in spaced relationship with respect to the base 11 in a manner permitting free vertical reciprocation and oscillation in a vertical plane parallel to the plane of swinging motion of the first bar 14. A rider 20 rigidly mounted on the bottom of the second bar 17 frictionally engages with the surface A of a cam B fixedly mounted upon an oscillating shaft C, it being understood that the rider is continually appressed against the cam surface A by action of gravity upon the assembly comprising the bars 14 and 17.

An intrinsically resilient arm 21 mounted near the distal free end of the bar 14 by means of a screw 22 extends upwardly and in spaced ad-

Jacency over the bar end substantially as shown and carries on its free end a contact element 23 suited to making electrical contact with an end portion 24 of a screw 25 adjustably mounted in a bracket 26 and held in position by a locknut 27.

In practice the screw 25 is advanced in the bracket 26 until electrical contact is established between the screw end 24 and the contact element 23, when the cam B is in the intermediate position illustrated in full line in Fig. 1, that is to say, when the bar 14 is at its maximum height during the cam motion.

An electrically conductive bar 28 mounted upon an insulative base 11 is electrically connected to the bar by a flexible cable 29 and is provided at its opposite end with a terminal screw 30 for facilitating connecting of an electrical cable to the switch, and in like manner a lug 31 is connected to the screw 25 by being positioned under the adjustment nut 27. It will follow from what has been set forth above that an electrical circuit may be completed or interrupted through the contact element 23 on the arm 21 and the screw head 24 and thus an electrical circuit including the terminal 30 and the lug 31 will be periodically altered in a manner related to the contour A of the oscillating cam B.

A rod 32 formed of electrically conductive material mounted in an opening formed in the top of the bar 17 and held in position by a screw 33 connected by a wire 34 to the electrically conductive bar 14 terminates at its top end in a ball 35. A pair of screws 36 and 37 mounted in standards 38 and 39 attached to the base 11 by screws 40 and locked in position by nuts 41 and 42 respectively are positionable in a manner such that the heads 43 and 44 respectively of said screws 36 and 37 act as stops limiting the motion of the ball 35 resulting from oscillation of the arm 17 due to changes in direction of motion of the cam B. As will be obvious from the foregoing statements, oscillation of the cam causes the electrical contacting of the ball 35 alternately with the screw heads 43 and 44 and, accordingly, the electrical circuits including the terminal 30 and the screws 36 and 37 intermittently are completed and interrupted. For facilitating connection of electrical cables to the screws 36 and 37, lugs 45 and 46 are respectively provided.

Having thus described the construction of the novel switching means according to the present invention, its preferred mode of use illustrated by its use in conjunction with a railroad signal of the wigwag type will now be described. In this instance the shaft C is connected to the pendulum signal which is oscillated by means such as a pair of magnets, one positioned on each side of a vertical plane intersecting the axis of the shaft cooperating with an armature mounted upon the shaft extending in a vertical position when the pendulum signal is at rest. The pendulum is set in motion by alternate energization of the magnets which in turn oscillates the armature with concomitant oscillation of the shaft and of the signal. For this purpose the electromagnets are connected to the screws 36 and 37, it being understood of course that the terminal 30 is connected to one side of the power supply line complementary to the side of the power supply line feeding the electromagnets whereby, when the ball 35 is positioned against one or the other of the screw heads 43 and 44, an electromagnet is placed in circuit with the

power supply. It is to be understood that the electromagnet in each instance connected to the power supply is the one which will tend to move the armature from its position at the time of connection.

As will be apparent from the detailed description of the structure of this invention, oscillation of the cam B results in oscillation of the bar 17 by reason of frictional engagement of the rigid rider 20 with the cam surface A. It is to be noticed that the distance between the pivot pin 18 and the cam surface upon which the rider rests is small in proportion to the distance between the pivot pin and the ball 35. Thus relatively small movement of the rider is reflected in relatively large or magnified movement of the ball. This feature promotes sensitivity of the device since change of direction of motion of the cam is substantially instantaneously reflected in oscillation of the bar. The switch comprising the contact element 23 and the screw head 24 is useful in controlling the operation of audible or physical signalling means functioning in conjunction with the wigwag signal. It is to be noticed that the circuit is completed through the switch only when the cam B is located in its intermediate position as shown in full line in Fig. 1, or in other words, the circuit including the switch is interrupted when the bar 14 descends due to the contour of the cam B near the ends thereof.

It is to be noticed that the ball 35 is vertically reciprocated during oscillation of the cam and hence it will be apparent to those skilled in this art that electrical contact between the ball and the screw heads 43 and 44 will be promoted because of wear of the parts resulting in clean contact surfaces.

It is to be understood that this invention is capable of extended application and is not confined to the precise illustrated forms nor described construction and, therefore, such changes and modifications may be made therein as do not affect the spirit of the invention nor exceed the scope of the appended claims.

Having thus described the present invention, what it is desired to secure by Letters Patent is:

1. A switch of the character described, comprising a vertically disposed base, a horizontally arranged bar pivoted at one end, an electric contact carried by the base above the free end of the bar, a vertically arranged bar intermediately pivoted to the horizontally arranged bar, electrical contacts carried by the base on opposite sides of the upper end of the vertically arranged bar for completing a circuit through the bar by the movement thereof in either direction, and a movable cam for engaging the lower end of the vertically arranged bar for swinging the same on its pivot and simultaneously causing the horizontally arranged bar to complete a circuit.

2. A switch of the character described, comprising a vertically disposed base, a horizontally arranged bar pivoted at one end, an electric contact carried by the base above the free end of the bar, a spring contact carried by the free end of the bar and adapted to engage the first mentioned contact, a vertically arranged bar intermediately pivoted to the horizontally arranged bar intermediate its ends, electrical contacts carried by the base on opposite sides of the upper end of the vertically arranged bar for completing a circuit through the bar by the movement thereof in either direction, and a movable cam for engaging the lower end of the vertically

arranged bar for swinging the same on its pivot and causing it to engage the contacts and simultaneously causing the horizontally arranged bar to make contact with the contact on the base upon the upward movement thereof.

3. A switch of the character described, comprising a vertically disposed base, a horizontally arranged bar pivoted at one end to the base, an electric contact carried by the base above the free end of the bar, a spring contact carried by the upper face of the bar and adapted to engage the first mentioned contact, a vertically arranged bar intermediately pivoted to the hori-

zontally arranged bar intermediate its ends, a contact carried by the base on each side of the upper end of the vertically arranged bar for completing a circuit through the bar by the 5 movement thereof in either direction, and an oscillating cam for engaging the lower end of the vertically arranged bar for swinging the same on its pivot to cause the bar to engage either of the contacts and simultaneously raising the 10 horizontally arranged bar to cause its spring contact to engage the contact on the base.
